ABSTRACT

An apparatus for developing an electrostatic latent image on an insulating layer having an electroconductive backing layer by spacing the layer from a developing electrode in a developing liquid where either or both the developing electrode and the electroconductive backing layer are grounded via resistance in the range of 10^6 – $10^{12}\Omega$.

APPARATUS FOR DEVELOPING ELECTROSTATIC LATENT IMAGE

BRIEF EXPLANATION OF THE DRAWING

FIG. 1 is a side elevation in longitudinal section of a sheet-shaped electrophotographic material, the right half portion of the surface thereof being electrically charged uniformly; FIG. 2 is a diagram showing the distribution of electric charge on the surface of the electrophotographic material illustrated in FIG. 1; FIG. 3 is a diagram showing the distribution of electric field in the direction perpendicular to the surface of sheet as derived from the distribution of electric charge illustrated in FIG. 2 in the absence of a developing electrode; FIG. 4 is a diagram showing the distribution of electric field as derived when a developing electrode is grounded directly and when it is grounded via a grounding resistance; FIG. 5 is a side elevation in longitudinal section of the developing electrode and the sheet-shaped electrophotographic material grounded via the grounding resistance; FIG. 6 is a diagram showing the distribution of electric charge derived where there is residual electric charge on the sheet surface; FIGS. 7 and 8 are diagrams showing the distribution of electric field as derived where the developing electrode is grounded directly and it is grounded via the grounding resistance respectively in the case of the diagram of FIG. 6; FIG. 9 through FIG. 11 and FIG. 14 are side elevations in longitudinal section of devices employed for putting this invention to working; and FIG. 12 and FIG. 13 are side elevations in longitudinal section of the structure of bearing of the roller illustrated in FIG. 11.

DETAILED DESCRIPTION OF THE INVENTION

This invention relates to an apparatus for developing electrostatic latent image. More specifically, this invention relates to a liquid developing apparatus so improved as to prevent the occurrence of fogging (a phenomenon which obscures the background to uniform density) due to residual electric charge and of streaks in the image.

Photoconductive insulating layers used in the field of electrophotography commonly process more or less residual electric potential. When a photoconductive insulating layer is electrically charged uniformly and subsequently exposed to light through an image, the electric charge is neutralized in the area where the layer has been exposed to light but the charge is retained intact on the photoconductive insulating layer in the area where the layer has escaped exposure to light. The electric charge to be neutralized increases with the intensity of light to which the layer is exposed. Thus, an electrostatic latent image conforming to the image which is represented in terms of light intensity is produced on the photoconductive insulating layer. In actuality, however, the degree of neutralization of electric charge stops growing proportionally with the rise of light intensity when the light intensity exceeds a certain level, beyond which the degree of neutralization growth is lowered. When the exposure to light through the image is stopped before complete neutralization of electric charge while the intensity of light for illumination is at its maximum, electric charge is suffered to remain even in areas where electric charge would otherwise be neutralized completely. Consequently, there is observed the so-called phenomenon of residual electric potential. When the exposure to light of high intensity

is continued until perfect elimination of residual electric potential, electric charge is neutralized excessively in areas where electric charge should not be neutralized beyond a certain level. Thus, it becomes no longer possible to produce an electrostatic latent image faithful to the original image, namely, properly proportional to the intensity of light used for exposure. In reality, therefore, there is followed a practice by which exposure is effected to such extent as to allow residual electric charge to occur to some extent and subsequently eliminate fogging due to residual electric charge by a suitable means. If the residual electric charge is developed faithfully, the background portion of image is fogged uniformly to produce a very unsightly image.

Heretofore, there has been proposed a practice of applying DC voltage to a developing electrode from an external source so as to give rise to electric potential equaling to the residual electric charge and consequently prevent the charge from producing fogging.

The conventional method and apparatus has been found defective in that toner particles are accumulated on the developing electrode and tend to come into contact with the electrostatic latent image and, as a result, smear the image. The loss of toner particles because of such accumulation has been heavy.

This invention relates to an apparatus for developing an image free from fogging due to residual charge and faithful to the original without requiring any external power source for the neutralization of residual potential.

One more defect in liquid development is occurrence of streaks in developed image. Next steps are usually involved in making a print by electrophotography: negatively charging an electrophotographic material, e.g., a paper bonded a photoconductive layer consisting of zinc oxide pigment in a resin binder, exposing it to form a latent electrostatic image, and developing the latent image with positively charged fine particles dispersed in insulating liquid. In this developing process, the flow of liquid developer produces streaks. The streaks are conspicuous in the case the flow of liquid developer is fast or the potential of the latent image is high. This phenomenon easily occurs when the liquid developer is poured into the space between the surface bearing a latent image and the developing electrode held close to the surface.

In a developing apparatus wherein an electrostatic latent image formed on an insulating layer of an electrophotographic material is disposed so as to confront a developing electrode with a minute opening and via a developing liquid having finely divided charged particles suspended in an electrically insulating liquid, this invention is characterized by conferring upon either or both of the developing electrode and the electroconductive layer of electrophotographic material such magnitude of grounding resistance as to permit prevention of excessive deposition of the aforementioned charged particles in the highlight zone of electrostatic latent image (the zone where the surface potential is smallest).

When the effect of developing electrode is maintained at an extremely high level throughout the period of development, even the smallest amount of residual potential due to residual charge is developed faithfully to produce fogging. Therefore, the spirit of this invention resides in conferring an adequate magnitude of grounding resistance upon either or both of the devel-

oping electrode and electroconductive layers of electrophotographic material, whereby toners are prevented from depositing in the zone of the least charge density within the electrostatic latent image (namely, the highlight zone of the image) and from occurrence of streaks without involving any significant decline of the effect of developing electrode in the zone of the highest charge density within the electrostatic latent image (the zone of high density in the image).

Now, the apparatus of this invention is described in further detail by referring to the drawing.

FIG. 1 shows a condition under which electric charge exists uniformly only in the right half portion of surface on the electrophotographic sheet 10. Numeral 11 denotes a photoconductive insulating layer which may be made of any known substance. Examples are amorphous selenium and photoconductive zinc oxide powder blended respectively with an insulating resin. Numeral 12 denotes an electroconductive base. The materials usable therefore include metal plate, plastic film treated so as to acquire electroconductivity, and paper. In the course of development, the base 12 is usually grounded. The latent image of FIG. 1 represents a case wherein positive charge is distributed uniformly in the right half portion of the upper side of the photoconductive insulating layer 11 while negative charge of an equal magnitude exists in the half portion of the lower boundary.

FIG. 2 is a graph illustrating the distribution of positive charge on the layer 11 as shown in FIG. 1. In the graph, the origin represents the boundary between the zone containing electric charge and the zone devoid of electric charge as shown in FIG. 1. It is assumed that the electric charge is uniformly distributed at a density of σ_0 .

FIG. 3 is a graph illustrating the composition of electric fields distributed perpendicularly to the plane of latent image as formed, in the absence of a developing electrode, within the electric field close to the latent image which is produced by distribution of electric charge as shown in FIG. 2. The distribution of electric charge shown in FIG. 2 has an entirely different shape from the distribution of electric field shown in FIG. 3. It is universally known that the phenomenon of edge effect results consequently. What should be noted at this point is the fact that even at the position satisfying $\sigma = 0$ in the diagram of FIG. 2, a negative electric field (with the electric field lying outward from the plane of latent image taken as a positive field) occurs in FIG. 3. This shall be referred to hereinafter as "opposite electric field."

FIG. 4 is a diagram illustrating the distribution of electric fields corresponding to those of FIG. 3 where a developing electrode is disposed to confront the surface containing the latent image at a fixed distance. In FIG. 4, the curve A represents a case wherein the grounding resistance of developing electrode (hereinafter expressed as "R") is very small ($R \approx 0$), while the curve B represents a case wherein the grounding resistance is very large ($R = 10^8 \Omega$, for example). When R becomes as small as this, a fair agreement is shown between distribution of electric charge and that of electric field. Yet, there still remains a very minor magnitude of opposite electric field. Particularly, the opposite electric field in the neighborhood of edge (the boundary of distribution of electric charge, namely, the origin of the graph of FIG. 4) is much larger than that

at a distance. The opposite electric field becomes much greater and the positive electric field becomes smaller in proportion as the value of R increases. Now, an explanation is made of the cause for which there occur the properties represented by the curve B.

FIG. 5 is a diagram of cross section illustrating the distribution of electric charge obtained when the developing electrode is spaced with a comparatively small distance from the surface of latent image, with the magnitude of grounding resistance R fixed at an extremely high level. Negative charge is induced through electrostatic induction in the area of the developing electrode confronting the positive charge of latent image. In the other portion of the developing electrode, positive charge substantially equivalent to the induced negative charge is induced. Because of a large value of R, the positive charge is not immediately discharged to the ground. This positive charge can move about with considerable freedom within the developing electrode. Of the negative charge distributed as opposite charge of latent image in the boundary of the electroconductive layer 12, the magnitude of negative charge equivalent to the negative charge induced on the developing electrode acquires freedom of mobility and eventually confronts the positive charge induced on the developing electrode where there exists no electric charge of latent image, as shown in FIG. 5. Consequently, an opposite electric field is formed at this portion and properties as represented by the curve B of FIG. 4 are believed to be acquired.

FIG. 6 illustrates the distribution of electric charge as obtained where there exists a residual charge σ_0' . This means that the electric charge $\sigma_0' = 0$ remains where the magnitude of electric charge should desirably become $\sigma_0' = 0$. The distribution of electric charge shown in FIG. 2 represents an ideal case, while the distribution of electric charge which is actually obtained by charging and exposure to light is as shown in FIG. 6.

FIG. 7 is a diagram which is contrasted to that of the distribution of electric charge in FIG. 6 and which corresponds to FIG. 4. The diagram represents a distribution obtained when the distance between the developing electrode and the latent image surface is fixed to comparatively small and the value of R is very small. As is evident from FIG. 7, the electric field at the portion where the residual charge σ_0' exists constitutes a positive field except in the neighborhood of the boundary of charge distribution. In the vicinity of boundary, the edge effect persists to induce negative electric field. When the distance between the developing electrode and the surface of latent image becomes very small (to several 10s of μ , for example), this edge effect becomes greatly decreased. When a liquid developer (having a microfine charged particles or toner particles with negative charge suspended in an insulative liquid) is supplied between the opening between the latent image surface and the developing electrode while the electric field is distributed as shown in FIG. 7, the toner particles are deposited in the portion of positive field. The consequence is that there occurs fogging due to residual electric charge.

The reason why the streaks shall occur has been guessed as follows. When the liquid developer is applied to the surface of the latent image, for example, applied to the left direction in FIG. 2, the toner particles, having negative charge in this example, are attracted to the positively charged right half area. Some

particles are carried downward from the area, and attach even to the no charged area. This is significant in the case the potential of charged area is the higher. In general, the counter electrical field (repulsion field) which prevents the attachment of toner particles appears on the no charged area. When the counter field is weak, the toner particles deposit on the no charged area. Though the repulsion field is strong in the absence of developing electrode as shown in FIG. 3, the presence of developing electrode makes the repulsion field weak and attracting field strong as shown in FIG. 4, curve A. Accordingly, developing electrode intensifies the streaks.

FIG. 8 is a diagram similar to that of FIG. 7 which corresponds to FIG. 4. The diagram represents a case wherein the value of R is fixed at a high level. In FIG. 8, the value of R is so large (corresponding to the curve B of FIG. 4) that the opposite electric field by σ_0 and the positive electric charge by σ_0' cancel each other, with a result that no positive field develops even at the portion where there exists residual charge. Therefore, no toner particle deposits at this portion. If the value of R is kept at a high level throughout the stage of development, there occurs the edge effect and there consequently ensues the so-called halo, a phenomenon of lack of toner deposition in the zone of the low charge density close to the boundary between the high charge density and the low charge density. Therefore, it must be avoided to keep the value of R at a high level throughout the entire period of development. Therefore, it becomes necessary to lower the value of R after lapse of a proper time. The length of this time is not fixed but varied by the properties of electrophotographic material and the resistance of liquid developer. Generally, the time is on the order of several tens of 35 seconds but may vary in the range of from several seconds to several minutes.

A description has been made as regards the grounding resistance to be imparted to the developing electrode. Similar effect can be obtained by perfectly grounding the developing electrode and allowing the electrophotographic material (the item denoted by numeral 12 in FIG. 1) to acquire grounding resistance. It is naturally permissible to have both developing electrode and electroconductive layer of electrophotographic material acquire grounding resistance. From the practical point of view, freedom of operation is increased and equipment is simplified by providing grounding resistance for the developing electrode. And, the device of this kind can be utilized for any kind of electrophotographic material. A specific means of conferring grounding resistance on the electroconductive layer of electrophotographic material consists in incorporating a resistance layer beneath the electroconductive layer of electrophotographic material or forming the aforementioned electroconductive layer on a base possessed of resistance.

FIG. 9 is a side elevation in cross section of one preferred embodiment for putting the method of this invention to working. Numeral 90 in FIG. 9 denotes an endless belt for conveying the sheet-shaped electrophotographic material 10, with the latent image surface thereof facing upwardly. As such belt, there may be used flexible metal belt, metal gauze belt, plastic belt, rubber belt, and fabric belt. The endless belt is driven around a pair of rollers 91 and 92. The sheet 10 is received on the belt 90 and conveyed from right to left.

The electroconductive layer 10 is grounded either via the belt 90 or independently. The sheet carrying plane of the belt 90 is inclined by an angle of about 5 to 20° with reference to the horizontal plane so as to facilitate the flow of developing liquid from right to left. The developing liquid 96 is stored in the container 95, scooped up by means of a pump which is not illustrated, and applied to the nozzle 94. At a substantially uniform distance upward from the sheet conveying surface of the endless belt 90, there is disposed a developing electrode 93 of metal plate grounded via the grounding resistance R . In one working example of the device illustrated in FIG. 9, R is $10^6\Omega$, the length of developing electrode in the direction of travel is 20 cm, the space between the developing electrode and the electrostatic latent image surface is 0.5 mm, and the conveying speed of sheet is 2 cm/sec.

FIG. 10 illustrates another preferred embodiment of this invention, namely, a device suitable for developing a web-shaped electrophotographic material 100 which is paid out of a roll. The web 100 retaining the electrostatic latent image on the outside is driven around the drum 101. The lower portion of the drum is held in contact with the liquid developer 104, and the developing electrode 102 having a curved plane is spaced with a suitable opening from the web 100 and grounded via a resistance R .

FIG. 11 is a side elevation in cross section of still another example for which the present invention proves particularly effective.

Numerals 111-1 through 111-5 denote rollers which are made to rotate at a fixed speed in one same direction, and numerals 112-1 through 112-5 are developing electrode rollers which are adapted to rotate at a fixed speed in one and same direction while confronting the aforementioned rollers. The rollers 111 and the rollers 112 may be held in intimate contact or may be separated slightly. The rollers 111 may be those made of metal or non-metal. In order that the rollers 112 may serve as developing electrode, they are required to be electroconductive on the surface or, if they are insulating on the surface, they are required to be electroconductive in the region close to the surface. To be specific, metallic rollers, having the surface thereof rendered insulating or semi-conductive, and insulating rollers having the surface thereof covered with an electroconductive layer are also used. Numerals 113-1 through 113-5 are nozzles used for spraying the rollers 112 with the developing liquid. The developing liquid is supplied by a pump not illustrated and fed to the nozzles. The pairs of rollers 111 and rollers 112 seize and transfer the sheet 10 containing the electrostatic latent image on the upper surface at a fixed speed toward right. The rollers 111 may be pressed by springing means against the rollers 112, or the rollers 112 may be mounted so as to rest gravitationally on the rollers 111. The rollers 112-1 through 112-5 are grounded via resistances R_1 through R_5 respectively. The resistances R_1 through R_5 may be either of an equal magnitude or of magnitudes decreasing or increasing at a fixed ratio.

FIGS. 12 and 13 illustrated concrete examples of the bearing intended to confer grounding resistance to the rollers 112 in the example shown in FIG. 11.

In FIG. 12, numeral 121 denotes a side plate made such as of metal so as to serve as the bearing of the rollers. On the side plate, there is provided a notch 115 for inserting the shaft 114 of rollers. To keep the shaft 114

of rollers from direct contact with the side plate 121, the resisting element 122 is disposed on the surface of the notch. A convenient resisting element for this purpose may be prepared by mixing silver or carbon particles into a resin or by blending electroconductive particles of silver or carbon into ceramic material.

FIG. 13 shows the shaft of rollers having a resisting element 131 disposed on the surface thereof instead of working on the side plate. As the resisting element, that which is similar to the resisting element 122 of FIG. 12 may be used.

In FIG. 12 and FIG. 13, if members 122 and 131 are insulating a resistor is connected between the side plate 121 and the shaft 114.

FIG. 14 illustrates still another preferred embodiment for which the present invention proves effective.

In FIG. 14, some numerals as those used in FIG. 10 are used to denote identical items. Numeral 140 is an electroconductive liquid, which may be water, an aqueous solution, or mercury. The liquid 140 is so selected that it will have a larger specific gravity than the developing liquid 104 and it will not be miscible with the liquid developer. Numeral 141 denotes the electrode inserted into the liquid 140 to serve the purpose of grounding the liquid 140 via the resistance R. The electrode 141 is not required where the liquid 140 has a high electroconductivity, but is required when the electroconductivity of the liquid 140 is relatively small (of the order of 10^4 , for example). Where an electroconductive liquid is used as the developing electrode (as disclosed in Japanese Patent Publication No. 44-6388, for example), fogging tends to occur because the space between the latent image surface and the developing electrode is very small. Accordingly, the method of this invention is extremely effective.

The magnitude of the grounding resistance to be used for the present invention cannot be fixed indiscriminately because it varies with the properties of liquid developer, the properties of electrophotographic material, and the nature of latent image. Where letters are reproduced, for example, R may be fairly large. In reproducing an image of continuous toner, details in the highlight area cannot be reproduced when R is too large. The highlight area suffers from fogging if R is too small. It is, therefore, desirable to minimize the value of R within the range which is free from formation of fogging. Empirically, it has been found that R is desired to fall in the range of $10^6 - 10^{12} \Omega$.

Even if the developing electrode is insulated after the liquid developer is poured between the developing electrode and the electrophotographic material the developing electrode is earthed through the liquid developer. As the volume resistivity of the liquid developer is about $10^{12} \Omega \text{ cm}$, on the assumption that the gap between the developing electrode and the surface of latent image is 0.1 mm and that the facing area is 100 cm^2 , the resistance of the liquid developer is

$$10^{12} \times 10^{-2} / 100 \text{ } 10^8 (\Omega)$$

What is claimed is:

1. Apparatus for developing an electrostatic latent image on an electrophotographic sheet of material optionally having an electroconductive backing layer, said apparatus comprising:

a developing electrode disposed adjacent to and spaced from said electrophotographic sheet of material;

means for providing a developing liquid between said developing electrode and said electrophotographic sheet of material to develop said electrostatic latent image;

resistive means for connecting either or both of said developing electrode and said electroconductive backing layer to a reference potential, the resistance of said resistance means being in the range of 10^6 to 10^{12} ohms, to prevent excessive background fogging and image streaking during development of said latent image.

2. Apparatus as in claim 1 wherein said reference potential is 0 volts.

3. Apparatus as in claim 1 including means for effecting relative movement between said electrophotographic sheet of material and said developing electrode.

4. Apparatus as in claim 3 including a container for storing said developing liquid and where said means for effecting relative movement between said electrophotographic sheet of material and said developing electrode includes an endless belt driven around a pair of rollers, said electrophotographic sheet being disposed on said belt for movement with respect to said developing electrode and said endless belt being inclined by an angle of about 5° to 20° with respect to the horizontal plane and where said means for providing said developing liquid between said electrophotographic sheet and said developing electrode is disposed adjacent the upper end of said endless belt to introduce said developing liquid between said electrophotographic sheet and said developing electrode so that it flows therebetween and then to said container for said developing liquid which is disposed beneath the lower end of said endless belt.

5. Apparatus as in claim 3 including a container for said developing liquid, said developing electrode being disposed in said developing liquid and where said means for effecting said relative movement between said electrophotographic sheet and said developing electrode includes a rotatably driven drum having disposed around a portion thereof said electrophotographic sheet, said portion being partially disposed in said developing liquid and adjacent said developing electrode.

6. Apparatus as in claim 3 including a first plurality of drive rollers disposed at one side of said electrophotographic sheet and where said developing electrode includes a second plurality of drive rollers respectively disposed adjacent said first plurality of drive rollers at the other side of said electrophotographic sheet, said first and second plurality of drive rollers moving said electrophotographic sheet therebetween.

7. Apparatus as in claim 6 including a shaft for each of said second plurality of rollers and a bearing for each of said shafts.

8. Apparatus as in claim 7 where said resistive means is disposed on the sides of said bearing and in electrical connection with said shaft and said bearing being connected to said reference potential.

9. Apparatus as in claim 7 where at least the outer portion of said shaft comprises said resistance means, said shaft being in electric contact with said bearing and said bearing being maintained at said reference potential.

10. Apparatus as in claim 3 including a container for said developing liquid and for a second liquid having a

larger specific gravity than and immiscible with said developing liquid and where said developing electrode is disposed in said second liquid and where said means for effecting relative movement between said electrophotographic sheet and said developing electrode comprises a rotatably driven drum having disposed around a portion thereof said electrophotographic sheet, said portion being disposed completely in said developing liquid and partially in said second liquid

whereby said developing liquid is dragged between said drum and said developing electrode due to the rotation of said drum to thereby effect said developing.

11. Apparatus as in claim 3 including a container for said developing liquid and an electrically conductive liquid having a larger specific gravity than and immiscible with said developing liquid, said electrically conductive liquid acting as said developing electrode and where means for effecting said relative movement be-

tween said electrophotographic sheet and said developing electrode comprises a rotatably driven drum having disposed around a portion thereof said electrophotographic sheet, said portion being completely disposed in said developing liquid and partially disposed in said electrically conductive liquid.

12. An apparatus for developing electrostatic latent image on an electrophotographic material comprising a developing electrode connected to ground potential via a resistance in the range $10^6 - 10^{12}\Omega$ to prevent excessive background fogging and image streaking during development of said latent image and an inclined electrophotographic material transferring mechanism, said developing electrode arranged with a small space to the surface of the electrophotographic material and a nozzle arranged about the top of the developing electrode for supplying a liquid developer between the developing electrode and the electrophotographic material.
